PER LEE B. GROJEAN, OF COLUMBUS, OHIO, ASSIGNOR OF ONE-HALF TO CHARLES W. OAKES, OF COLUMBUS, OHIO

SANITARY MILK CABINET

Application filed August 18, 1930. Serial No. 476,153.

The present invention is directed to improvements in sanitary milk cabinets for household use.

The primary object of the invention is to provide a device of this character so constructed that a bottle or bottles containing milk can be placed in the cabinet and the cover thereof locked to prevent surreptitious removal of the bottles from the cabinet.

10 Another object of the invention is to provide a device of this kind constructed in such manner that the cover of the cabinet cannot be locked until a milk bottle has been placed therein.

15 Another object of the invention is to provide a device of this type wherein the cover thereof will be substantially closed, but not locked, when the cabinet is empty, thus preventing the entrance of dust and moisture.

20 Still another object of the invention is to provide a device of this character provided with novel means for preventing locking of the cover until a bottle has been placed in the cabinet, the construction being extremely 25 simple, durable, efficient in operation, and one which can be manufactured at a small cost.

With these and other objects in view, this invention resides in the novel features of construction, formation, combination and arrangement of parts to be hereinafter more fully described, claimed and illustrated in the accompanying drawings in which:—

Figure 1 is a top plane view, the cover elevated.

Figure 2 is a vertical sectional view, the cover being lowered, but not locked.

Figure 3 is a similar view, showing the cover locked.

40 Referring to the drawings, 1 designates the cabinet preferably formed from sheet metal and of the shape shown. This cabinet is provided with ears 2 in order that securing devices may be engaged therewith to secure the cabinet to a suitable support.

45 The cabinet has mounted therein cells 3 formed from aluminum, three cells being illustrated, but it will be of course understood that the number may be decreased or increased, as desired. As shown the outermost

cells are of a size to receive quart size bottles, while the middle cell is somewhat smaller for receiving a pint or half pint size bottle.

The front wall 4 of the cabinet is provided with a pair of spaced bearings 5 in which the ends of the shaft 6 is journaled, there being also carried by said wall a lock 7 having in the upper end of its casing a slot 8 for receiving the catch carried by the cover to be hereinafter described. The lock is of conventional form and may be unlocked by a key.

The shaft has fixed near its ends levers 9, which depend into the outer cells 3, the purpose of which will appear later.

The wall 4 is further provided with a recess 10 in which the lock 7 fits, and secured to said lock is one end of a coil spring 11, the other end of which is fixed to an arm 12, and serves to normally hold the arm yieldably engaged with the lock casing. The arm 12 is fixed centrally to the shaft 6 and is aligned with a lever 13, which depends into the central cell 3.

15 The upper end of the arm 12 has formed therein a slot 14 for slidably receiving a pin 15 carried by a slide plate 16, which is adapted to close the slot 8 of the lock 7 when the cells are empty, and at which time the spring 11 will retain the plate 16 in position to close said slot 8, and will further hold the respective levers in inclined positions within the cells so that they will be in positions to be swung toward the front wall of the cabinet when a bottle is placed in either cell. Obviously when a bottle swings a lever forwardly the plate 16 will be slid inwardly since this operation rocks the shaft 6.

20 The cover 17 is hingedly connected to the rear wall of the cabinet and carries a hook-catch 18 for movement into the slot 8 of the lock for engagement with the usual lock bolt thereof, not shown. The cover is further provided with a flange 19 which will overlap the upper edge of the cabinet to effectively close the same when the cover is unlocked, but in a substantially closed position, thus preventing the entrance of water and dust. It will be apparent that when the cells are empty the plate 16 will cover the slot 8 and prevent the catch-hook 18 from entering the

same, thereby preventing locking of the cover.

When it is desired to place a milk bottle in the cabinet it is only necessary to lift the cover and upon placing a bottle in a cell the engaged lever 9 will swing forwardly, thereby rocking the shaft 6, whereupon the plate 16 will slide inwardly and uncover the slot 8. When this has been done the cover is swung down and the hook-catch will enter the slot and lock the same. The bottles can then be removed from the cabinet by using a key adapted to the lock.

Since the cells are formed from aluminum they will be rust proof and will aid in retaining the bottles in a cool state when placed therein in warm weather. The cells may be supported in the cabinet in any suitable manner, and are surrounded by a packing or insulation 20 of Balsam wood pulp, which serves to retain the bottles cool in warm weather and prevent freezing of the contents in cold weather.

What is claimed is:—

- 25 1. A cabinet having cells therein, a shaft pivotally supported by the cabinet and having levers fixed thereto which depend into the cells, and arm carried by the shaft, a plate connected with the arm, a lock casing carried by the cabinet and having a slot therein, a cover for the cabinet having a hook-catch carried thereby, means for yieldably holding the plate in position for closing the slot to prevent entrance of the hook-catch, said levers being operable upon depositing a bottle in a cell to rock the shaft to cause the arm to slide the plate to uncover the slot, as and for the purpose set forth.
- 30 2. A cabinet having a plurality of cells therein, a lock casing carried by the cabinet and having a slot therein, a shaft journaled on the front wall of the cabinet and having levers carried thereby depending into each cell, a cover hingedly connected to the cabinet and having a hook-catch thereon, a plate slidably and pivotally connected to an arm on the shaft, a spring connecting the arm and lock casing serving to hold the levers in angular positions within the cells and the plate in a position to close said slot to prevent entrance of the hook-catch thereinto, thereby preventing locking of the cover, said levers being adapted to swing when engaged by a bottle deposited in a cell to rock the shaft to slide the plate in a direction to uncover the slot to permit entrance of said hook-catch into the slot.
- 35 3. A device of the class described comprising a cabinet having a cell therein, a lock carried by the cabinet, a cover for the cabinet, said lock having a slot-formed therein, a hook-catch carried by the cover, a plate normally closing said slot and preventing entrance of the hook-catch thereinto to hold the cover in a substantially closed position, an

arm slidably and pivotally connected to the plate, a lever associated with the arm and depending into the cell, and operable by a bottle when deposited in a cell to move the plate to uncover the slot and permit entrance of the hook-catch thereinto.

In testimony whereof I affix my signature.

PER LEE B. GROJEAN.
